UNITED STATES PATENT OFFICE.

NATHAN U. WALKER, OF WELLSVILLE, OHIO.

CHIMNEY-CAP.

SPECIFICATION forming part of Letters Patent No. 231,463, dated August 24, 1880.

Application filed August 30, 1879.

To all whom it may concern:

Be it known that I, NATHAN U. WALKER, of Wellsville, in the county of Columbiana and State of Ohio, have invented a new and

5 useful Improvement in Chimney-Caps; and I do hereby declare the following to be a full, clear, and exact description thereof, reference being had to the accompanying drawing, forming part of this specification, which shows 10 an elevation, partly in section, of a chimney cap or coping and crocks embodying my invention.

Brick chimneys are liable to be injured by rain and frost, which penetrate the crevices, 15 loosen the mortar, and cause the chimney to get out of plumb and fall to pieces. It is also impracticable to give to chimneys constructed entirely of brick many desirable forms of ornamental finish. To overcome the first of these 20 difficulties chimneys have, in some instances, been formed partially or entirely of a single metal casting, or a single tube of fire-clay or artificial stone, and in other instances with separable caps or copings and crocks; but, 25 owing to the nature of the means devised for securing the parts, the latter constructions have been of metal, the same being impracticable in making the articles of more frangible material, as the loss from breakage in 30 transportation and handling was so great.

The object therefore of my invention is to produce a separable cap or coping and crock of such construction that it may be readily made from clay, terra-cotta, artificial stone, 35 and the like, will not be liable to be broken or rendered useless in transportation or handling, and to which any desired ornamental shape may be readily given.

To this end it consists in providing the cap 40 or coping with the usual horizontal and vertical flanges to cover and inclose the chimney, and in addition thereto with cleats or equivalents, which form a dovetailed recess adapted to receive the expanded end or like projections 45 on the base of the crock, and in employing, in conjunction with such a cap or coping, a crock having an expanded or dovetailed base, as will hereinafter more fully be set forth.

I will now proceed to describe my invention 50 more specifically, so that others skilled in the art to which it appertains may apply the same.

In the drawing, *a* indicates the chimney cap

or coping, which is formed with the vertical or downwardly-projecting flange *c*, adapted to inclose and protect the upper end of the 55 chimney.

b indicates the horizontally-projecting flange, the extent of which will depend not only on the ornamental finish to be given to the cap or coping, but also upon the diameter of the 60 crock and extent of flue-opening desired. In any case the flange *b* will be of sufficient width to give a firm support to the crock and admit of the formation thereon of cleats for securing the crock.

d *d* indicate cleats formed on the upper surface of the cap or its flange *b* on the two sides of the flue-opening. These cleats are undercut or form a dovetailed recess, as shown, for the reception of the base of the crock.

e indicates a crock, to which any desired ornamental shape may be given; but its base must be expanded, as at *f*, or given the form of a dovetail or its equivalent, in order to correspond to the recess formed by the cleats *d*.

The cap or coping *a* will, of course, be coextensive with the top of the chimney, and, if there are several flues, should preferably be provided with vertical flanges *i*, or intermediate ribs corresponding to the division wall 80 or walls of the flues, in order to obtain a better support for the cap, while the crocks may correspond in number to the flues, in which case each crock will be held by its own set of cleats *d*, or in the recess formed thereby.

In use, when the cap or coping *a* has been applied to the top of the chimney, which can readily be done by unskilled labor, the crocks *e* may be secured in place by sliding the expanded base or dovetails *f* between the cleats *d* or into the corresponding recess or recesses on the top of the cap or coping; and, if desired, the crocks may be rendered additionally secure by the use of cement.

A cap or coping and crocks formed in accordance with my invention may be of terra-cotta, fire-brick, artificial stone, or the like, and will not possess parts liable to change shape in the manufacture or break off in the subsequent handling or transportation, so that loss thereon will be reduced to the minimum, and a cheap and ornamental finish for chimneys can be had.

I am aware that protective caps or copings

for chimneys have heretofore been made with vertical and horizontal flanges, and that detachable crocks have been secured thereto by lugs and projections, and do not herein broadly claim the same; but in such cases the parts have necessarily been formed of metal, as the means of attaching the parts would not permit the use of more frangible material, such as fire-brick, &c. Therefore,

Having thus described my invention, and fully pointed out its essential and distinguishing features, what I claim, and desire to secure by Letters Patent, is—

1. A chimney cap or coping having horizontal and vertical flanges, as at *b c*, and a dove-

tailed recess formed by cleats *d d*, adapted to receive the dovetailed or expanded base of a crock, substantially as and for the purpose specified.

2. The chimney cap or coping having the horizontal and vertical flanges *b c* and the intermediate vertical flanges or ribs *i*, corresponding to the division-wall of the flues, substantially as and for the purpose specified.

In testimony whereof I, the said NATHAN U. WALKER, have hereunto set my hand.

NATHAN U. WALKER.
